AUTOMATICALLY OPENING AND CLOSING
LIFTING HOOK

Frederick R. Loney, Denver, Colo.

Application May 24, 1949, Serial No. 94,964

3 Claims. (Cl. 294—115)

1

This invention relates to a lifting tongs for use on derrick and hoist lines for lifting and loading various materials and is more particularly designed for gripping and lifting railroad car wheels.

The principal object of the invention is to provide a highly efficient, automatically operating tong which, when lowered against an object, will automatically open to receive the object, and which, when elevated, will automatically close to securely grip the object.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the improved tongs;

Fig. 2 is a side view thereof in the open position;

Fig. 3 is a similar view in the closed position; and

Fig. 4 is a detail, fragmentary view of the hinge portion of a jaw used in the improved tongs.

The improved tongs employs two arcuate, hook-shaped oppositely facing gripping jaws 10 and 11 hingedly mounted together upon a suitable hinge pin 12. The lower extremities of the jaws 10 and 11 are formed with gripping edges 19 for gripping any article to be lifted. The hinged extremity of the jaw 10 is bifurcated to form two similar, parallel hinge pads 13. The hinged extremity of the jaw 11 is narrowed to form a relatively flat tongue portion 14 which is rotatably positioned between the two pads 13 of the jaw 10.

The pads 13 are both provided with a straight, elongated pin opening 15, the axis of which extends radially from the axis of the hinge pin 12. The tongue 14 of the jaw 11 is provided with a crooked or bent slot 16, the upper portion of which aligns with the upper portion of the first slot 15 when the jaws 10 and 11 are in the closed position of Fig. 2, and the lower portion of which is offset to one side so as to align with the lower portion of the first slot 15 when the jaws are in the open position of Fig. 3.

This places the upper portion of the slot 16 on a radial line A—A in Fig. 4 extending from

2

the axis of the pin 12, and places the center of the lower portion of the slot on a second radial line B—B, Fig. 4, approximately 30° to one side of the line A—A.

5 A clevis bolt 17 extends through both slots 15 and 16 and is mounted in an inverted, U-shaped hanging clevis 18 by means of which the tongs are supported. When the jaws are lowered against a supporting surface, such as indicated at 21 in Fig. 2, the clevis pin 17 will move downwardly toward the hinge member 12. In moving downwardly, it will be forced to travel toward the line B of Fig. 4, and in so doing will swing the two jaws 10 and 11 away from each other, as indicated in Fig. 3.

When the clevis 18 is lifted, the clevis pin 17 will travel toward the upper extremities of both slots 15 and 16, swinging the lower extremities of the jaws inwardly to grip the article to be lifted, as shown in Fig. 2.

20 While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A lifting tong comprising: a first arcuately curved, hook-like gripping jaw; a second similar gripping jaw; a hinge pin hinging the two jaws together in opposed relation adjacent their upper ends, both jaws having portions extending upwardly beyond said hinge pin in overlapping relation; a vertically disposed relatively straight slot formed in the overlapping portion of one jaw above the hinge pin and disposed radially thereof; a relatively crooked slot formed vertically in the overlapping portion of the second jaw, said slots being arranged so that when said jaws are 30 in the closed position, the upper portion of both slots will be in registry, and when in the open position, the lower portions of both slots will be in registry and extending diagonally of each other; and a lifting member extending through both slots and arranged to travel throughout the lengths of the slots.

2. A lifting tong comprising: a first arcuately curved, hook-like gripping jaw; a second similar gripping jaw; a hinge pin passing through and hinging the two jaws together in opposed relation adjacent their upper ends, both jaws extending beyond said hinge member in overlapping relation, the extending-beyond portion of the first jaw being bifurcated to form two parallel, spaced-50 apart, flat pads, the extending-beyond portion of

3

the second jaw being flattened to form a relatively flat tongue which is positioned between the pads of the first jaw; a relatively straight, elongated, slotted opening formed in each pad above the hinge pin with its axis lying on a line extending radially from said hinge pin; an angular, slotted opening formed in said tongue above the hinge pin and having upper and lower portions disposed diagonally of each other, and a lifting member including a pin passing through all of said slots, the said end portions of the angular slotted opening being arranged so that the upper portion thereof will register with the slotted openings in the pads and extend radially of the hinge pin when the jaws are in the closed position, and the lower portion of the angular slot being in registry with the lower ends of the slotted openings in said pads and extend diagonally thereof and radially of the pin of the lifting member when the jaws are in the open position.

3. A lifting tong comprising: a first arcuately curved, hook-like gripping jaw; a second similar gripping jaw; a hinge pin hinging the two jaws together in opposed relation adjacent their upper portion, both jaws having portions extending upwardly beyond said hinge pin in overlapping relation, the upwardly extending portion of the first jaw being bifurcated to form two parallel, spaced-apart, flat pads, the upwardly extending portion of the second jaw being flattened to form a relatively flat tongue which is positioned between the pads of the first jaw; a relatively

straight, elongated, slotted opening formed in each pad with its axis lying on a radial line from said hinge pin; an angular, slotted opening formed in said tongue and having upper and lower portions disposed diagonally of each other, the end portions of said angular opening being arranged so that the upper portions thereof will register with the slotted openings in the pads and extend radially of the hinge pin when the jaws are in the closed position, the lower portion of the angular slot being in registry with the lower end of the slotted openings in said pads and disposed diagonally thereof when the jaws are in the open position; a clevis pin passing through all of said slotted openings and lying parallel to said hinge member in upwardly spaced relation thereto; and an inverted U-shaped clevis straddling the upwardly extending portions of the jaws and engaging the extremities of said clevis pin, the free lower extremities of said jaws having relatively sharp, article-engaging ends formed with beveled lower edge faces.
